UNITED STATES PATENT OFFICE

LOUIS JOSEPH JEAN BAPTISTE CHÉNEAU, OF PARIS, FRANCE

TEMPERATURE-RESPONSIVE DEVICE

Application filed June 27, 1927, Serial No. 201,933, and in Belgium July 3, 1926.

The present invention relates to temperature responsive devices and more particularly to those of the type adapted to be used in connection with fire-alarm systems.

5 One of the objects of the invention is to provide a temperature responsive device which is not responsive to slow temperature changes but which will respond quickly to a rapid change in temperature.

10 Other objects will appear in the course of the following description of preferred embodiments of the invention shown in the accompanying drawings in which:

Fig. 1 is a diagrammatic section through one form of the device;

15 Fig. 2 is a diagrammatic longitudinal section through a second form of the device;

Fig. 3 is a section taken on line 3—3 of Fig. 2;

20 Fig. 4 is a longitudinal section of a third form of the device, and

Fig. 5 an end view of the embodiment of the invention shown in Fig. 4.

The embodiment of the invention shown in Fig. 1 comprises a pair of concentric tubes 1 and 2 closed at their extremities by end closures 3 and 4 common to both tubes. Tube 2

25 is made of a thin material which is a good conductor of heat, while tube 1 is formed of material which is a poorer conductor of heat than the material of tube 2.

30 An orifice 5 is formed in the wall of tube 1 adjacent the end closure 4 and a diaphragm 6 of corrugated metal (preferably nickel plated copper) extends transversely of the tube 1 adjacent said orifice 5, thus forming a pair of isolated chambers 7, 7' within the tube 1. A screw 8 mounted in but insulated from end closure 4, extends longitudinally of the

35 chamber 7 and contacts with diaphragm 6 when the latter is in its position of "rest". The screw 8 also serves as one terminal of an electric circuit, and a second terminal 16 is mounted on closure 3. The apparatus operates as follows: Assuming the device to be

40 properly connected in circuit with an electric or luminous or sound signal system and that the temperature surrounding the device is slowly rising, heat will pass through wall 2

45 and raise the temperature of the air or other

fluid contained in the space between tubes 1 and 2; but since tube 1 is capable of conducting heat, the temperature of the fluid in chamber 7 will also rise and diaphragm 6 will remain at rest.

50 If on the contrary, the temperature surrounding the device rises suddenly, the fluid in chamber 7 will be more quickly heated than that in chamber 7' and the resulting difference in pressure will cause

55 diaphragm 6 to flex away from the end of the screw 8 and interrupt the flow of current between terminals 16 and 8. This interruption of current flow may be utilized as in

French Patents No. 327,152 and No. 320,702, to close a circuit connected to the fire alarm.

60 It will be noted that the device is so constructed that, when the temperature within the chamber 7' becomes approximately the same as that within the chamber 7, dia-

65 phragm 6 will flex back into contact with the end of the screw 8. In other words, after the device has been heated for a certain length of time or, if it be permitted to cool,

70 all the working parts will be restored to the position of "rest" and the fire-alarm signal

75 will cease automatically.

In the embodiments of the invention shown in Figs. 2 and 3, the tube 2 of Fig. 1 is replaced by a series of tubes 2' which, like the tube 2, are good conductors of heat, the tube

80 1 being here again a poorer conductor of heat. A closure 3 seals tube 1 and tubes 2' at one end. The other ends of tubes 2' open into a chamber 7'' formed by an end closure 4'

85 and a wall 9 closing the corresponding end of tube 1. An open-ended cylinder 6° has one of its ends connected to a circular orifice in wall 9 and a piston 6² works in said cylinder with a minimum of friction.

Piston 6² is normally held by a compression spring 6' in contact with the end of a screw 8 mounted in but insulated from the closure 4'. Current is supplied to the device by means of

90 leads connected to screw 8 and to a terminal 16 mounted on closure 3. This embodiment

95 of the invention operates in a manner similar to the one shown in Fig. 1. The piston 6², which replaces the diaphragm 6 of Fig. 1, is subject to the differences between the pres-

995 sures existing in the chambers 7 and 7' and

100

operates to break the circuit between the terminals 8 and 16 upon a rapid rise of temperature.

The embodiment of the invention shown in Figs. 4 and 5 comprises an inner tube 1 and an annular chamber 2'' surrounding the tube 1 and closed at both of its ends, the tubes forming the chamber 2'' having the same relative heat conducting properties as the tubes 1 and 2 in Fig. 1 and the tubes 1 and 2' in Fig. 3. One end of tube 1 is sealed by closure 3 and the other end by wall 9 and a group of elements 6°, 6², 6' similar, respectively, to the elements 6°, 6' and 6² illustrated in Fig. 2. The fluid in chamber 2'' is free to pass from said chamber through one or more conduits 5 to act on piston 6² which forms the movable wall separating the chambers 7 and 7'. The rigid portions of chamber 7 consist of a cylindrical member 11', insulating disc 4, a plug 12 of conductive material threadedly engaging with disc 4 and held in place by a nut 12', and a screw 8 mounted in a bore of the plug 12 and having its end normally contacting with the piston 6². Current is led to screw 8, through plug 12 from a cap 13, threadedly engaging with the latter, said cap being in contact with a longitudinally adjustable binding post 8' carried by a bar 14 which extends diametrically of one end of a perforated cylinder 15 surrounding but spaced from the outermost of the tubes which form the chamber 2''. One end of the tube 1 is supported within and spaced from the innermost tube which forms the chamber 2'' by the binding post 8', cap 13', disc 4, and member 11'. The other end of the tube 1 is supported by strips 10 which bridge the space between the tube 1 and the innermost tube of the chamber 2''. This embodiment of the device functions in substantially the same manner as the one represented in Fig. 2, the special end structure being designed to prevent tampering with or derangement of the setting screw 8.

Each of the devices shown in Figs. 1, 2 and 3, and 4 and 5 may be constructed as above described or each may be provided, either with a very small orifice such as that shown at 20 in Fig. 2, by means of which the two chambers 7 and 7' communicate one with another and which assures the equilibrium under all conditions except when very abrupt temperature changes take place, or with very small orifices, such as those shown at 21 and 22 in Fig. 4, said orifices allowing the fluid in each chamber to escape slowly to the atmosphere as the temperature slowly rises, thus rendering the device sensible only to very abrupt changes of temperature.

The invention is not to be taken as limited to the particular constructions hereinbefore described but embraces as well such variants as will be obvious to those skilled in the art.

What I claim is:—

1. A device of the class described comprising a central chamber having lateral walls formed of a relatively poor conductor of heat, a second chamber external to said central chamber and enclosing the latter, said second chamber having a wall formed of a relatively good conductor of heat, a pressure responsive partition forming at least part of a common wall separating said chambers from one another, electrical contacting means associated with said partition, and an electrical terminal in conductive relation with one of the walls of one of said chambers.

2. A device of the class described comprising in combination a central chamber, a second chamber external to and concentric with, said central chamber, a pressure responsive partition separating said chambers, and electrical contacting means positioned adjacent said partition and adapted to contact therewith.

In testimony whereof I have hereunto set my hand.

LOUIS JOSEPH JEAN BAPTISTE CHÉNEAU.
